CLOTHES OR LIKE WRINGER

Robert D. O'Callaghan, Des Moines, Iowa

Application October 4, 1937, Serial No. 167,188

3 Claims. (Cl. 68—271)

The principal object of my invention is to provide a clothes or like wringer that is capable of successfully receiving and wringing liquid saturated objects of considerable thickness.

A further object of this invention is to provide a clothes or like wringer that is highly efficient and possesses great flexibility between its two compression rollers.

A still further object of my invention is to provide a wringer wherein the entire upper roller assembly is hinged at one of its ends and capable of being swung to a vertical position for the removal of the entire assembly.

A still further object of this invention is to provide a clothes or like wringer having a rigid, removable and concealed frame member for absorbing all of the strain applied on the wringer rollers.

A still further object of my invention is to provide a clothes or like wringer that is provided with safety device permitting the immediate disengagement of the upper roller relative to the lower roller when the operator so desires.

A still further object of this invention is to provide a clothes or like wringer having a cam lever for the ready locking and closing of the wringer roller assembly.

A still further object of my invention is to provide a clothes or like wringer wherein the water or liquid wrung from the cloth or like is conducted or conveyed back into the tub or like from which the cloth is ordinarily drawn without the liquid contacting the cloth on its return travel.

A still further object of this invention is to provide a clothes or like wringer that is economical in manufacture, durable and efficient in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a side plan view of my complete wringer ready for use.

Fig. 2 is an end sectional view of my wringer and more fully illustrates its construction.

Fig. 3 is a bottom plan view of the spring compression elements and cable control for holding the upper wringer roller in yielding relationship to the lower roller.

Fig. 4 is a side partial sectional view of the frame assembly of my wringer more fully illustrating its construction.

Fig. 5 is an enlarged bottom view of a portion of the upper assembly bar of my wringer showing the safety release.

Fig. 6 is an enlarged end view of the cam forcing assembly more fully illustrating its construction.

Fig. 7 is an end view of a portion of the frame of the wringer showing the method of hingedly securing the upper roller assembly to the tension bars of the device.

There are a great number of wringers on the market. These wringers have a number of serious disadvantages. One of the chief disadvantages of wringers now in use is the fact that there is not enough maximum clearance between the rollers when they are under pressure. Usually the upper roller of the device has a short coil spring for forcing it into contact with the lower roller. This makes it impossible to force heavy clothing between the rollers, thereby hindering the efficiency of the wringer and increasing the amount of work necessary to wash clothes of a heavy nature such as quilts, blankets and the like. There are indeed hinged upper rollers on some wringers. However, these rollers hinge in a plane parallel with the longitudinal center of the upper roller and at best only have four or five inches clearance between the rollers at the maximum open position of the upper carriage. This is unsafe inasmuch as, although they have safety releases, the clearance between the rollers at their maximum is not enough to obviate a chance of accident of a serious nature. Furthermore, the upper roller assembly of these rollers can not be removed for cleaning, inspection and the like.

Another of the principal objections to wringers now on the market is that the outer cover is used as a supporting frame making necessary a casting or the like of heavy material. This increases the weight and the cost of these wringers and furthermore, places the strain or torsion upon the complete wringer frame. Therefore it makes it very easy to warp or spring the wringer frame assembly when heavy loads are imposed upon the rollers. I have overcome these disadvantages as will be appreciated and as hereinafter more fully set forth.

Referring to the drawings, I have used the numeral 10 to designate an elongated horizontal frame portion having a cross supporting plate 11 at one of its ends and a horizontal plate 12 secured to its other end. I have used the numerals 13 and 14 to designate two upwardly extending supporting members secured to the horizontal plate 11 spaced apart from each other and having their upper extremities bent outwardly as shown in Fig. 7. The numerals 15 and 16 designate two similar upwardly extending supporting members secured to the plate 12 as shown in Fig. 2. I have used the numerals 17 and 18 to designate bolts or rods slidably mounted in the outwardly extending portions of the upwardly

extending frame members 13 and 14 respectively. Similarly, the numerals 19 and 20 designate two bolts slidably mounted in the outwardly extending portion of the vertical frame members 15 and 16 respectively. I have used the numeral 21 to designate a bolt or the like positioned below the frame member 10 and having thereon the opposing compression springs 22 and 23 as shown in Fig. 3.

10 The numerals 24 and 25 designate plates slidably mounted on the bolt or rod 21 and to which are attached the central portions of cables or the like 26 and 27 respectively.

The two ends of the cable 26 extend over pulleys 28 rotatably mounted on the horizontal plate 11 and thence have their extreme ends secured to the bolts 17 and 18. Similarly, the two end portions of the cable 2 extend over pulleys 29, which are rotatably secured to the plate 12 and thence has its extreme ends secured to the two bolts 19 and 20 as shown in the drawings. The numeral 30 designates a hook member formed on the upper end of the bolt 17. The numeral 31 designates an eye formed on the upper end of the bolt 18. I have used the numeral 32 to designate a U-shaped member having one end in hinged engagement with the eye 31 and its other end portion in hinged engagement with the hook 30 as shown in Fig. 7. The numeral 33 designates a horizontal frame bar having one end rigidly secured to the U-shaped member 32. Secured to this bar 33 adjacent its end portions are the downwardly extending bearing hangers 34 and 35 as shown in Fig. 1. Rotatably mounted between these bearing members is an ordinary wringer roll or like 36. I have used the numeral 37 to designate a flange plate which has its two horizontal end portions engaged by the heads of the bolts 19 and 20 and thence extending upwardly as shown in Fig. 2. I have used the numeral 38 to designate a trigger lock secured to the frame bar 33 adjacent the plate 37 and having its lock capable of engagement with a slot cut in the plate 37 at times. This lock is operatively secured to a rod 39 having a tension spring 40 thereon for keeping the trigger lock in an extended position normally. The numerals 41 and 42 designate handles pivotally secured to the frame bar 33 and having their end portions in operative functional engagement with the rod 39 as illustrated in Fig. 5 of the drawings.

Thus when the upper frame assembly is pivoted in the hook 30 and the eye 31 to a closed position, the lock 38 will engage the slot in the plate 37, locking the roller 36 in its normal position. When it is desired to open the upper assembly and pivot it to a vertical position such as is shown by dotted lines in Fig. 1, either of the handle members 41 or 42 may be touched, thereby drawing the sear of the lock 38 out of engagement with the edge of the slot in the plate 37, permitting the free hinging movement of the roller assembly to a vertical position. Sometimes it is difficult to close the upper roller assembly until the lock 38 snaps into position due to the pressure against the roller 36. I have facilitated this closing movement by providing the closing cam 43 which is rotatably mounted on the upper end portion of the bar 33 and has a handle member 44 to facilitate its operation. The numeral 45 designates a hook secured to and extending upwardly from the central portion of the plate 31. Thus when the roller assembly is partially closed, the handle member 44 is rotated to a position as indicated by dotted lines

in Fig. 6. This allows the cam 43 to contact the hook 45, exerting a leverage against the hook 45 and forcing the roller assembly to close to a position where the catch of the lock 38 is received by the slot in the plate 37. The handle member 44 is then released and will return to its normal position by virtue of an ordinary barrel spring. In this position, the cam 43 does not interfere with the ready opening of the upper roller assembly as the horizontal face of the 10 cam 43 will clear the end of the hook 45 as shown in Fig. 6.

I have used the numeral 46 to designate the lower roller of my wringer which is rotatably supported within the frame in the usual manner and is geared to a suitable source of power through the usual gear box 47 and shaft 48. This roller is positioned below and parallel to the roller 36 and is the driven roller of the wringer.

I have used the numeral 49 to designate a hood 20 which is placed over the upper roller assembly and through which the handle members 41 and 42 project for accessibility. The numeral 50 designates the hood over the lower wringer assembly and the mechanism proper. The numeral 51 designates the aprons of the wringer integrally formed with the hood or cover 50 and sloping downwardly and away from the roller 46 as shown in Fig. 2. It will be noted that there is a gap between the roller and the upper marginal edge of these aprons 51 to allow water squeezed from the clothes or like to drop on the inside of the apron 51. The numeral 52 designates a drain board positioned below the apron 51 and slanting outwardly and downwardly. Thus water will run between the drain 52 and the apron 51 back into a tub or like on either side of the wringer at the will of the operator and dependent upon the rotation of the rollers relative to each other.

The numeral 53 designates a drain guide pivotally secured to the frame of the wringer directly below the roller 46 and in a horizontal plane as shown in Fig. 2 and Fig. 4 of the drawings. Rigidly secured to this drain guide 53 is an upwardly extending arm which has a point 55 thereon capable of frictional engagement with the end of the roller 46. Thus when the roller 46 is rotated in a counter clockwise direction with reference to Fig. 2 of the drawings, the clothes will be pressed between the rollers 36 and 46 and the frictional engagement of the pin or point 55 with the end of the roller will cause the drain guide 53 to be tilted or rotated about its axis to a position as shown by dotted lines 55 in Fig. 2, thus guiding the water wrung from the clothes back into the tub or container from which the clothes were removed.

The practical operation of my device is as follows: The wringer in its normal position for use is as shown in Fig. 1 of the drawings. Clothes are introduced, dependent upon rotation of the wringer or rollers, between the rollers 36 and 46. The friction of the rollers upon the clothes will pull the clothes through the wringer in the ordinary manner. The drain guide 53 will, as hereinbefore explained, be rotated to guide the water back to the side of the wringer from which the clothes are introduced to the wringer. The water wrung from the clothes will travel between the apron 51 and the drain 52, thus keeping the returning water away from the clothes and guiding it back to a suitable container. As the upper roller is yieldingly and slidably supported above the lower roller, a great thickness of clothes will

be accommodated. This merely allows the upper roller assembly to move upwardly by pulling on the bolts 17, 18, 19 and 20 against the compression of the springs 22 and 23 respectively through the medium of the cables 26 and 27. By positioning these springs 22 and 23 in a horizontal plane below the wringer frame, a great amount of travel is experienced allowing for an enormous capacity between the rollers 36 and 46. Should something happen in the process of wringing clothes requiring the ready and immediate release of tension between the rollers, either one of the handle members 41 or 42 may be touched, thereby pulling the rod 39 and releasing the trigger catch lock 38 from engagement with the plate 37.

This allows the entire upper roller assembly to freely pivot on the hook 30 and the eye 31, and the wringer may be opened to a complete vertical position as illustrated in Fig. 1. To again place the device in operation, the upper roller assembly is merely swung to a horizontal position. Should the pressure necessary to engage the lock 38 be too great, the cam lever arm 44 is merely rotated to a position as shown by dotted lines in Fig. 6, engaging the cam 43 with the hook 45 and exerting a leverage for the complete closure of the upper roller to a locked position. The handle member is then, through the medium of an ordinary spring, returned to a position adjacent the hood 48. When the upper roller assembly is in a position as shown by dotted lines in Fig. 1, the pivoting point engaged by the hook 30 can be removed therefrom by slight rotation and then disengaged from the eye 31 for completely removing the upper roller and its attendant mechanism. This vertical hinging of the upper roller provides for the maximum amount of clearance between the rollers when necessary. Obviously, the frame portion comprising the plate 10, the plates 11 and 12, and the vertical arms 13, 14, 15 and 16 can be constructed in one piece. This frame is then placed within the hood 50. The bolts 17, 18, 19 and 20 can then be inserted from the outside of the hood 20, the heads of the bolts 19 and 20 engaging and holding the plate 37. The cables 26 and 27 can then have their end portions secured to each of the bolts 17, 18, 19 and 20 by any suitable means. This frame can be made of stainless material or the like and absorbs all of the strains and torsion in the operation of the wringer.

As the whole upper roller assembly including the hood is held in yielding relationship to the roller 46, the whole assembly is raised when thick items of clothing are run between the rollers, thus providing unobstructed clearance between the rollers and eliminates any interference with the hood when obtaining the maximum clearance required. The only limitation to the clearance between the rollers is the amount of travel necessary for the springs 22 and 23 to reach their maximum compression. Thus it will be seen that I have provided a wringer that has a great amount of usable clearance between the rollers, that is sturdy, that has a removable frame, that has a full floating upper roller assembly, and from which the entire upper roller assembly may be removed. Furthermore, my device is equipped with safety devices and is simple in construction and operation, thereby fulfilling my objects and overcoming the many objections and limitations applied to devices of this class now on the market.

Some changes may be made in the construction and arrangement of my improved clothes or like wringer without departing from the real spirit and purpose of my invention, and it is my intention to cover by my claims any modified forms of structure or use of mechanical equivalents which may be reasonably included within their scope. 5

I claim:

1. In a wringer, a lower frame member, an upper frame member vertically slidably mounted to said first frame member, a roller rotatably mounted in each of said frame members, a horizontal rod below said first frame member, two compression springs embracing said rod, a means for limiting the movement of each of said springs on said rod, a cable guide member at each end of said first mentioned frame, a cable having one end operatively secured to one of said compression springs and its other end secured to one end of said second frame member; said cable engaging one of said cable guide members and having only one bend in its length from its point where it is operatively secured to said spring and secured to said second frame, and a second cable having one end operatively secured to the other said compression spring and its other end secured to the other end of said second frame member; said second cable engaging the other of said cable guide members and having only one bend in its length from the point where it is operatively secured to said spring and to said second frame member. 10

2. In a wringer, a horizontal frame member, a second frame member slidably secured to said first frame member, a horizontal rod below said first frame member, a threaded nut on each end of said rod, two compression springs embracing said rod and having their outer ends operatively engaging the two threaded nuts on the two ends of said rods respectively, a cable element having its central portion operatively engaging one of said springs and its two ends secured to said second frame, the second cable element having its central portion operatively engaging the other said spring and its two ends secured to said second frame member, and a roller rotatably mounted in each of said frame members. 20

3. In a wringer, a lower frame, an upper frame, vertically slidably mounted; relative to said first frame, a roller rotatably mounted in each of said frames, a rod member below said first frame, a cable guide member at each end of said first mentioned frame, a cable, a means for adjustably securing one end of said cable to said upper frame, a second cable, a means for adjustably securing said second cable to said upper frame, a resilient means on said rod for yieldingly holding the other end of both of said cables in a direction toward said rod; said first mentioned cable being operatively secured to one end of said upper frame, engaging one of said cable guide members and having only one bend in its length from the point where it is operatively secured to said upper frame to a point in the vicinity of said rod and said second cable operatively engaging the other end of said upper frame, engaging the other of said cable guide members and having only one bend in its length from the point where it is operatively secured to said upper frame to a point in the vicinity of said rod. 30

ROBERT D. O'CALLAGHAN.
